UNITED STATES PATENT OFFICE.

JOSEPH CLINTON BARNES, OF SUMMIT, MISSISSIPPI.

TENSION DEVICE FOR FENCE-WIRES.

SPECIFICATION forming part of Letters Patent No. 624,730, dated May 9, 1899.

Application filed September 6, 1898. Serial No. 690,291. (No model.)

To all whom it may concern:

Be it known that I, JOSEPH CLINTON BARNES, of Summit, in the county of Pike and State of Mississippi, have invented a new and useful Improvement in Tension Devices for Fence-Wires, of which the following is a full, clear, and exact description.

The object of my invention is to provide a tension device for fence-wires by means of which the wires will be firmly supported and held while the stays, which are usually placed between the posts, are twisted together.

A further object of the invention is to provide a device of the character indicated which will be simple and inexpensive and which can be quickly and readily applied to any fence.

The invention consists in the novel construction and arrangement of parts, as will be hereinafter fully set forth, and pointed out in the claims.

Reference is to be had to the accompanying drawing, forming a part of this specification, in which the figure is a perspective view of the improvement applied to a fence in process of construction.

In the drawing, 10 are the fence-wires; A, a post to which the wires are secured by staples 11; 12, a short post to which the lowermost fence-wire is secured, and C the stays, which are to be twisted together between the several wires. These stays may be of any preferred form; but as shown they consist of a strip of wire 20, bent at one end to form a hook 19, which engages the lowermost wire. The other end of the wire is then carried up over the uppermost wire and downward and coiled, as at 21 and 22, around the intermediate wires, the end 23 of the wire extending downward adjacent to the hook 19.

In order to firmly support and hold the fence-wires 10 while the stays are being twisted together, I employ the tension device B, applied to the fence adjacent to one of the stays, as shown in the drawing. This tension device consists of a rectangular frame having clamps 13 at its bottom, which clamps are usually hook-shaped and are adapted to pass over the top of the lowermost fence-wire, as shown. A

second clamp 14, also in the nature of a hook, is made to engage with the under face of the 50 uppermost fence-wire 10, and the clamp 14 is attached to a chain 15, cable, or the like, said chain or cable being connected with a windlass 16, mounted upon the aforesaid frame, the windlass being operated through the medium 55 of a crank 17. From the sides of the frame project supporting-arms 18, upon which all of the fence-wires are made to rest.

By the above-described construction the fence-wires will be held at proper distances 60 apart while the stays C are being twisted to secure them to said fence-wires.

Having thus described my invention, I claim as new and desire to secure by Letters Patent—

1. A tension device for fence-wires, comprising a frame having supports projecting from its sides and upon which the wires rest, a clamp on the bottom of the frame for engaging the bottom wire, and means carried by 70 the top of the frame for engaging the top wire to exert a strain thereon, substantially as described.

2. A tension device for fence-wires, consisting of a frame having clamps adapted to 75 bear downwardly upon the lowermost fence-wire, supports for all the fence-wires, a windlass mounted upon the upper portion of the frame, and a clamp connected to the windlass and adapted to exert upward tension on the 80 uppermost fence-wire, substantially as described.

3. A tension device for fence-wires, consisting of a frame provided with hooks on its bottom for engaging the bottom wire and with 85 two sets of laterally-projecting arms for supporting all the wires, a windlass mounted on the frame, and a chain or cable secured to the windlass and having a hook at its end for engaging the top wire, substantially as de- 90 scribed.

JOSEPH CLINTON BARNES.
